UNITED STATES PATENT OFFICE.

THOMAS J. STRICKLER, OF WASHINGTON, DISTRICT OF COLUMBIA, ASSIGNOR OF ONE-HALF TO CHARLES D. HOLDEN.

AUTOMOBILE SPEED GOVERNOR.

Application filed February 25, 1927. Serial No. 170,900.

The present invention relates to an automobile speed governor of the type actuated by a fan belt, and associated with the fuel regulating throttle for opening and closing the throttle valve under predetermined conditions.

More specifically, the invention has reference to a device of this character which includes a centrifugal speed governor constructed to automatically operate a novel mechanism which is connected with the throttle valve for permitting a maximum and uniform speed of movement to be maintained whether running on the level surface or up or down an inclined surface.

My principal aim, is of course, to generally improve upon structures of this class by providing a novel organization of details such as have been carefully selected and associated to render the device advantageous from the standpoint of the manufacturer owing to features of compactness and convenience, simplicity, and efficiency in operation.

The particular construction of each and every part as well as its office in the new arrangement, will become more readily apparent from the following description and drawings.

In the drawings:

Figure 1 is a top plan view of the complete device showing it associated with fragmentary portions of the automobile.

Fig. 2 is an enlarged detail sectional view taken approximately upon the plane of the line 2—2 of Fig. 1.

In the drawings, the reference character 1 designates the motor block, 2 designates the carburetor, 3 the control crank arm for the throttle valve, 4 a stationary anchor, 5 the steering rod housing, 6 and 7 the customary control rods on opposite sides thereof.

The invention comprises a suitable supporting bracket 8 fastened to the motor block and carrying an appropriate bearing 9. Journaled for rotation in this bearing is a shaft 10 on one end of which is a flanged pulley 11, over which the ordinary fan belt 12 is trained.

An arm 13 is connected with the bearing 9 and includes a portion 14 operating as an additional bearing. The shaft 10 extends through and beyond the last named bearing. Mounted on the extending end portion is a

fork 15 which is fastened to the shaft for rotation therewith. This fork operates as a carrier for the pivotally mounted centrifugal governor arm 16.

These governor arms are located on diametrically opposite sides of a sliding cap 17 fitted on the shaft 10 as shown better in Fig. 2. On one end of this cap is a collar 18 in which inwardly extending fingers or guides of the governor arms 16 are located. Incidentally the governor arms are connected together by a spring which resists the outward swinging movement. On the opposite end of the cap is a reduced neck carrying a rounded head 19.

The head 19 is adapted to engage in an adjustable screw 20 carried on the depending arm 21 of the bell crank 22. This bell crank is pivoted as at 23 to the free end portion of the supporting arm 13. In this position it will be noticed that the set screw 20 is adjustable toward and from the head 19 to regulate the sensitivity of operation.

Pivoted connected as at 25 to the horizontal arm 24 of the bell crank is a throttle operating arm 26 which is in turn connected with a right angularly disposed control rod 27. The rod is connected with the crank arm 3 on the throttle valve. Also connected with this arm 26 is a link 28 adjustably connected with the bell crank arm 24. This permits the angularity of the arm 26 with respect to the arm 24 to be varied and retained in adjusted position.

A relatively long coiled spring 29 is connected at one end to the intermediate portion of the rod 27 and is anchored at its opposite end on the stationary part 4. The intermediate portion of this frame is however, connected with a hand operated throttle lever 30. That portion of the spring between the lever and the support 4 is under tension and normally serves to hold the throttle in a slightly open position. That portion between the lever 30 and its point of connection with the rod 7 is contracted and is of such rigidity when thus contracted, that it functions substantially as a push rod for operating the rod 27.

For example, by grasping the lever 30 and moving the same in a direction from left to right, movement will be imparted to the rod 27 through the medium of the compressed and substantially rigid portion of the spring 29. This allows the operator to have some-

what independent control of the automatic feed regulating device.

In operation it is plain to be seen that the speed obtained by the propeller shaft will be transmitted through the medium of the fan belt 12 to the small pulley 11. This will rotate the shaft 10 in its bearings. In so doing, the head or fork 15 rotates with the shaft, and when a certain speed is obtained, 10 the governor arms will fly out in the direction of the arrows against the tension of the springs.

Obviously, the special construction of these governor arms will act upon the collar 18 to shove or slide the cap 17 outwardly upon the shaft 10. This will eventually bring the head 19 into engagement with the adjusted set screw 20 and will rock the bell crank 22 upon its pivot 23. It follows that 20 through the medium of the arm 26, and the rod 27, this throttle valve will be actuated.

It is obvious from the foregoing description, that I have evolved and produced a novel automatically operating device controlled by the propeller shaft of the engine for actuating the throttle valve. The device is exceptionally sensitive and capable of being adjusted so that it can be regulated or set for a certain maximum speed, where- 30 by when this speed is exceeded, the device will come into play to cut down the charge and to cause the machine to resume the normal speed limit.

It is believed that persons skilled in the art to which the invention relates will be able to obtain a clear understanding of the invention after considering the description in connection with the drawings. Therefore, a more length description is thought unnecessary.

Minor changes in re-arrangement of parts, shape, size, and mounting may be resorted to within the scope of the adjoined claims.

Having thus described my invention, what 45 I claim as new is:—

1. In a speed regulator of the class described, a bearing, a shaft mounted for rotation in said bearing, said shaft being provided with a pulley adapted to be driven 50 by a fan belt, an attaching bracket for the bearing, a supporting arm connected with the bearing, a bell crank pivotally mounted on the supporting arm, an operating connection associated with one arm of the bell

crank for a throttle valve, centrifugal governor actuated means on the shaft cooperable with the remaining arm of the bell crank, together with adjustable means carried by the last crank arm for cooperation with said means. 55

2. In a structure of the class described, a bearing and attachment means therefor, a supporting arm associated therewith, a shaft mounted for rotation in the bearing, a bell crank pivotally mounted on said supporting arm, a throttle operating arm pivotally connected to the bell crank, and an adjusting and retaining link connected with the bell crank arm and said operating arm, a throttle operating rod connected with the operating arm and a governor actuated device associated with the shaft and said bell crank. 60

3. In a structure of the class described, a bearing and attaching means therefor, a supporting arm associated therewith, a shaft mounted for rotation in the bearing, a bell crank pivotally mounted on said supporting arm, a throttle operating arm pivotally connected to the bell crank, an adjusting and retaining link connected with the bell crank arm and said operating arm, a throttle operating rod connected with the operating arm, and a governor actuated device associated with the shaft and said bell crank, 70 said device comprising a slide, and an adjustable set screw carried by the bell crank and co-operable with said slide. 75

4. In a structure of the class described, a bearing, a bell crank, means for supporting the bell crank from said bearing, a shaft mounted for rotation in said bearing, a belt pulley on said shaft, a fork fixedly mounted on said shaft for rotation with said shaft, centrifugal governor arms carried by the arms of the said fork, said shaft projecting through and beyond the arms of said fork, a cap slidably mounted on the extending end of said shaft, said shaft having a head on one end, said centrifugal governor arms having operating connection with the other end of the cap, throttle operating means connected with one arm of said bell crank, and an adjustable set screw carried by the other arm of the crank and cooperable with a head on said cap. 80

In testimony whereof I affix my signature.

THOMAS J. STRICKLER.
